UNITED STATES PATENT OFFICE

ROBERT H. MUELLER, OF DECATUR, ILLINOIS, ASSIGNOR TO MUELLER CO., OF DECATUR, ILLINOIS, A CORPORATION OF ILLINOIS

SPRAY NOZZLE

Application filed October 24, 1929. Serial No. 402,235.

The invention relates to a spray nozzle, and more particularly to that class of spray nozzles used as shower heads.

The object of the invention is to provide a shower head, whereby the type of spray can be changed, as desired, that is, either a very fine thin spray, or a heavy coarse spray.

Another object of the invention is to provide a shower head, in which the spray can be practically cut off without the use of the usual valves.

Still another object of the invention is to provide a shower head which will be free from scale, or foreign matter which generally lodges in the spray holes, causing great inefficiency.

With these and other objects and advantages in view, attention is called to the drawings, in which:

20 Figure 1 is a vertical cross-section of the shower head assembly, and

Figure 2 is a plan view of the bottom of the shower head showing the spray holes therein.

Referring more particularly to the drawings, the invention provides the usual ball and socket joint, comprising the nut 1 internally screw threaded at 2 for a pipe connection, and externally screw threaded at 3 to receive the socket member 4.

25 A spring 5 is placed within the socket member, and rests upon the packing such as a washer 6 which in turn fits upon the ball member 7 which has an orifice at its top, as at 8. Suitable packing such as a washer 9 is placed between

30 the bottom of the socket member and said ball member. Extending downwardly from the ball member through the bottom of the socket member, is a tubular member 10 having attached thereto, at its lowermost portion

35 in any suitable manner, a disc 11. Screw threads 12 are provided near the upper portion of the tubular member 10, and at a point substantially midway the said tubular member, is a collar 13 integrally or otherwise attached thereto, which is provided with screw threads 14.

40 An enclosing member 15 substantially bell shaped fits around the tubular member 10 and is provided with internal screw threads 50 to correspond with those on said tubular

member. Packing is provided at 16 between the enclosing member 15 and the tubular member 10. A bottom 17 is attached in any suitable manner to the enclosing member 15, and has on its inner surface projections 18 through which are apertures 19. It will be noted that the apertures are considerably larger than those ordinarily used, and that there are no apertures directly below the outlet of tubular member 10. The disc 11 attached to the tubular member 10 completely covers the apertures in the bottom of the enclosing member, sufficient clearance being left between said disc and the walls of the enclosing member to allow the latter to be moved against or away from the disc 10.

Handles 20 may be provided on the enclosing member to facilitate operation thereof.

The operation of the device is extremely simple and efficient. Relative movement of the bell shaped enclosing spray member and the disc 11 regulates the flow of the water and the desired type of spray. When the shower head is in an open position, the streams of water attain greater volume and less velocity; when the shower head is in a nearly closed position a diminished velocity and fine mist-like spray result. The water may be completely shut off by bringing the shower head tightly against the disc.

70 In order to clean the inside of the shower head from scale or foreign matter which lodges on the projections about the openings, it is simply necessary to tightly screw the bell shaped enclosing spray member against the disc 11 and, in so doing, grind the scale or foreign matter into small particles, whereby as soon as the shower head is opened, the water will carry the scale and foreign matter out through the enlarged holes.

75 It will be understood that the embodiment of the invention disclosed herein is illustrative and not restrictive, and that various changes in the form, construction and arrangement of parts may be made within the spirit and scope of the following claims.

I claim:

80 1. In a spray nozzle, a tubular outlet member, a disc-like portion secured to the lower end thereof, and an enclosing spray member

- associated with said tubular member, said members being adjustable relative to each other to regulate the spray.
2. In a spray nozzle, a tubular outlet member, a disc-like portion secured to the lower end thereof, and a substantially bell-shaped enclosing spray member associated with said tubular outlet member, said members being adjustable relative to each other to regulate the spray.
3. In a spray nozzle, a tubular outlet member, a disc-like portion secured to the lower end thereof, and an enclosing spray member adjustably secured on said tubular member.
- 15 4. In a spray nozzle, a tubular outlet member, a disc-like portion secured to the lower end thereof, an enclosing spray member associated with said tubular member, and means to regulate the flow of water therethrough.
- 20 5. In a spray nozzle, a tubular outlet member, a disc-like portion secured to the lower end thereof, a substantially bell-shaped member adjustably secured on said tubular outlet member, and a perforated disc attached at the bottom of said bell-shaped member.
- 25 6. In a spray nozzle, a tubular outlet member, a disc-like portion secured to the lower end thereof, an enclosing member adjustably secured on said tubular outlet member, and means to divert the flow of water from said tubular member.
- 30 7. In a spray nozzle, a tubular outlet member, an enclosing spray member adjustably secured on said tubular outlet member, and means to diffuse the water through the bottom portion of said enclosing spray member.
- 35 8. In a spray nozzle, a tubular outlet member, a disc-like portion secured to the lower end thereof, and an enclosing spray member adjustably secured on said tubular outlet member, the bottom of said enclosing spray member having apertures therein.
- 40 9. In a spray nozzle, a tubular outlet member, a disc-like portion secured to the lower end thereof, and an enclosing spray member adjustably secured on said tubular outlet member, the bottom of said enclosing spray member having apertures therein at points without the circumference of said tubular outlet member.
- 45 10. In a spray nozzle, a tubular outlet member, a disc-like portion secured to the lower end thereof, and an enclosing spray member adjustably secured on said tubular outlet member, the bottom of said enclosing spray member having projections on its inner surface, said projections having apertures therein.
- 50 11. In a spray nozzle, a tubular outlet member, a disc-like portion secured to the lower end thereof, and an enclosing spray member adjustably secured on said tubular outlet member, the bottom of said enclosing spray member having circular projections on its inner surface, said circular projections having apertures therein.
- 55 12. In a spray nozzle, a tubular outlet member having a disc-like portion at its lower end and an enclosing spray member adjustably secured on said tubular outlet member, the bottom of said enclosing spray member having circular projections on its inner surface to form seats for said disc-like portion, said circular projections having apertures therein.
- 60 13. In a spray nozzle, a tubular outlet member having a disc-like portion at its lower end and an enclosing spray member adjustably secured on said tubular outlet member, the bottom of said enclosing spray member having circular projections on its inner surface at points without the circumference of said tubular outlet member to form seats for said disc-like portion, said circular projections having apertures therein.
- 65 14. In a spray nozzle, a tubular outlet member, an imperforate disc-like portion secured to the lower end thereof, and an enclosing spray member, the interior diameter of which is larger than said disc-like portion, the tubular outlet member and the spray member being adjustable relative to each other to regulate the spray.
- 70 15. In a spray nozzle, a tubular outlet member, an imperforate disc-like portion secured to the lower end thereof, and an enclosing spray member, the interior diameter of which is larger than said disc-like portion, and provided with apertured projections on its inner surface, the tubular outlet member and the spray member being adjustable relative to each other to regulate the spray.
- 75 In testimony whereof I have hereunto set my hand.
